UNITED STATES PATENT OFFICE

166,657

LAMP BASE

Louis Benigni, Chicago, Ill.

Application February 4, 1952, Serial No. 18,378

Term of patent 7 years

(Cl. D48—20)

To all whom it may concern:

Be it known that I, Louis Benigni, a citizen of the United States, residing at Chicago, in the county of Cook and State of Illinois, have invented a new, original, and ornamental Design for a Lamp Base, of which the following is a specification, reference being had to the accompanying drawing, forming a part hereof.

In the drawing:

Fig. 1 is a front perspective view of a lamp base, showing my new design; and

Fig. 2 is a rear perspective view thereof.

I claim:

The ornamental design for a lamp base, substantially as shown.

LOUIS BENIGNI.
